(57) **CLAIM**

The ornamental design for massage chair, as shown and described.

DESCRIPTION

FIG. 1 is a perspective view of a first embodiment of the massage chair according to the present invention;

FIG. 2 is a front view of a first embodiment of the massage chair according to the present invention;

FIG. 3 is a side view of a first embodiment of the massage chair according to the present invention;

FIG. 4 is a rear view of a first embodiment of the massage chair according to the present invention;

FIG. 5 is a top view of a first embodiment of the massage chair according to the present invention;

FIG. 6 is a perspective view of an alternate embodiment of the massage chair according to the present invention;

FIG. 7 is a front view of an alternate embodiment of the massage chair according to the present invention;

FIG. 8 is a side view of an alternate embodiment of the massage chair according to the present invention;

FIG. 9 is a rear view of an alternate embodiment of the massage chair according to the present invention; and,

FIG. 10 is a top view of an alternate embodiment of the massage chair according to the present invention.

Environmental features that are not part of the claimed design are shown in broken lines.
